CLAIM

The ornamental design for a modular building, as shown and described.

DESCRIPTION

FIG. 1 is a top perspective view of a modular building incorporating our new design;

FIG. 2 is a bottom perspective view thereof;

FIG. 3 is a left side view thereof;

FIG. 4 is a left side view thereof;

FIG. 5 is a front view thereof;

FIG. 6 is a rear view thereof;

FIG. 7 is a top plan view thereof; and,

FIG. 8 is a bottom plan view thereof.

The broken lines shown in the drawings illustrate portions of the modular building that form no part of the claimed invention.
